PRESSURE REGULATOR FOR COM- PRESSED GASES

Guglielmo Balsamo, Via Asiago 26, Milan, Italy

Filed Apr. 17, 1963, Ser. No. 74,493

Claims priority, application Italy Nov. 29, 1962

Term of patent 7 years

(Cl. D91—3)

FIG. 1.

FIG. 4.

FIG. 1 is a side elevational view of a pressure regulator for compressed gases embodying my new design;
FIG. 2 is an end view taken from the left of FIG. 1;
FIG. 3 is an end view taken from the right of FIG. 1;
and

FIG. 4 is a top plan view thereof.

The dominant features of my invention reside in the portions shown in full lines in the drawing.

I claim:

The ornamental design for a pressure regulator for compressed gases, substantially as shown and described.
